Specification for Design.

Patented Aug. 8, 1922.

Application filed October 11, 1921. Serial No. 507,154. Term of patent 14 years.

To all whom it may concern:

Be it known that I, FRED G. MAYER, a citizen of the United States, residing at Richmond, in the county of Wayne and State of Indiana, have invented a new, original, and ornamental Design for Phonograph Tables, of which the following is a specification, reference being had to the drawing accompanying the same and forming part thereof.

The figure is a front perspective view of a phonograph table suitable for library use, showing my new design.

I claim:

The ornamental design for a phonograph table, as shown.

FRED G. MAYER.
